UNITED STATES PATENT OFFICE

159,352

BLOUSE OR SIMILAR ARTICLE

Sally Lewis, Brooklyn, N. Y.

Application March 22, 1950, Serial No. 8,683

Term of patent 3½ years

(Cl. D3—25)

To all whom it may concern:

Be it known that I, Sally Lewis, a citizen of the United States of America, residing in Brooklyn, county of Kings, and State of New York, have invented a new, original, and ornamental Design for a Blouse or Similar Article, of which the following is a specification, reference being had to the accompanying drawing, forming part thereof.

Fig. 1 is a front view of a blouse or similar article, showing my new design.

Fig. 2 is a rear view thereof.

Fig. 3 is an enlarged fragmentary view of the blouse portion illustrating the embroidery in detail.

I claim:

The ornamental design for a blouse or similar article, substantially as shown and described.

SALLY LEWIS.
